UNITED STATES PATENT OFFICE.

ALFRED A. WOHLAUER, OF NEW YORK, N. Y.

ELECTRIC SWITCH.

No. 889,566.

Specification of Letters Patent.

Patented June 2, 1908.

Application filed June 25, 1907. Serial No. 380,735.

To all whom it may concern:

Be it known that I, ALFRED A. WOHLAUER, a citizen of the Empire of Germany, residing in New York, in the borough of 5 Manhattan, county and State of New York, have invented certain new and useful Improvements in Electric Switches, of which the following is a specification.

This invention relates to an improved electric switch or cut-out by which the spark on 10 breaking contact is confined in a vacuum-tube so that danger of fire and the wearing out of the metallic contacts is prevented and an effective and quickly operated switch obtained.

With this end in view, the invention consists in an electric switch or cut-out which 15 embodies contacts mounted so that they oppose one another, and a vacuum-tube partly filled with mercury mounted to turn between 20 said contacts and to electrically connect and disconnect the same.

The invention consists further in other 25 novel features of construction, as will be hereinafter pointed out in the description and claims.

In the accompanying drawings, Figures 1 and 2 represent front-elevations of my improved electric switch or cut-out, showing 30 the same respectively in position for closing the circuit, and when the same is broken, Fig. 3 is a vertical central section of the same through the vacuum-tube, on line 3, 3, Fig. 1, Fig. 4 is a vertical transverse section on 35 line 4, 4, Fig. 2, and Fig. 5 is a detail side-view of the vacuum tube.

Similar letters of reference indicate corresponding parts throughout the several figures.

Referring to the drawings, *a* represents 40 the foundation-plate of my improved electric switch or cut-out. The foundation-plate *a* is preferably made of porcelain or other suitable insulating material. It is provided with a central depression *b* and a 45 raised rim *b*¹ concentric thereto. At diametrically-opposite points of the rim *b*¹ are arranged, flush with the inner circumference of the rim, metallic contact-plates *d*, *d* which are fastened to the rim by screws *d*¹ or other 50 suitable fastening devices. Across the depression *b* is placed a vacuum-tube *e*, which is made of glass, and provided with metallic caps *e*¹ at the ends, said caps having the same curvature as and forming close contact with 55 the contact-plates *d*, *d*.

The vacuum-tube *e* is closed at both ends

and provided at each end with an electrode *f* of carbon, tungsten or other suitable material, the electrodes being sealed-in in a manner similar to the electrodes in the well-known mercury-lamps. The vacuum-tube is partly filled with mercury, after which it is exhausted and sealed in the usual way, the small tip *t* in the glass-tube indicating the proper place for the pump-connection. The 60 vacuum-tube *e* is swiveled at the center by means of a metallic ring *e*² which is insulated from the tube by a rubber-ring *e*³. The ring *e*² has a thumb-piece *h* at its upper side for operating the switch while its opposite or 65 lower part is provided with a stud or pin *h*¹ which enters a central socket *h*² in the foundation plate *a*. The stud or pin *h*¹ serves as a pivot and the socket *h*² as a step-bearing for 70 the same.

When the vacuum tube is placed in position in the foundation plate *a* and its metallic-caps *e*¹ in contact with the metallic contact-plates *d*, *d*, as shown in Fig. 1, the mercury establishes contact between the two 80 terminal electrodes *f*, so that the circuit is closed. When the vacuum-tube is turned into inclined or vertical position, out of contact with the diametrically-disposed contact-plates, the uppermost electrode or terminal is first moved out of the mercury and thereby the contact with the contact-plates interrupted and the circuit opened as no current can then flow through the unsubmerged 85 electrode. When the vacuum tube is partly 90 turned into inclined position, a small arc is formed between one electrode at the point where the mercury recedes from the electrode. This, however, immediately disappears with 95 currents below 0.75 amperes, as the vacuum in the glass-tube prevents the keeping up of the arc and neutralizes the spark.

When the vacuum-tube is in a vertical position, the contact with the contact-plates is entirely interrupted, no current passing 100 through the vacuum-tube owing to the entire interruption of the contact of the caps with the contact-plates on the foundation-plate. When the switch is turned back into horizontal position the contact of the caps 105 with the contact-plates, as well as between the mercury and electrodes, is established, and thereby the circuit closed again with little, if any, sparking taking place.

The advantages of my improved electric 110 switch or cut-out are that sparking is reduced to a minimum owing to the gradual

breaking or closing of the circuit, and that a very effective and easily-operating switch is obtained, especially for high tension purposes.

Having thus described my invention, I claim as new and desire to secure by Letters Patent:

1. In an electric switch or cut-out, the combination, with the opposing contacts, of a mercury-containing vacuum-tube swiveled 10 intermediately of its length to move in the plane of said contacts and arranged to engage at its ends with the latter.

2. In an electric switch or cut-out, the combination, with the opposing contacts, of 15 a swiveled vacuum-tube to establish electrical communication between said contacts, said vacuum-tube being partly filled with mercury and provided with sealed in electrodes, and metallic end-caps to coact with 20 said contacts.

3. In an electric switch or cut-out, the combination, with the opposing contacts, of a vacuum-tube swiveled between the same, said tube being partly filled with mercury 25 and provided with sealed in electrodes, and metallic end-caps to coact with said contacts.

4. In an electric switch or cut-out, the combination of a foundation-plate having a socket, contacts mounted at either side of

said socket, a mercury-containing vacuum- 30 tube to establish electrical communication between said contacts, and a ring embracing said tube and having a pivot turning in said socket and a thumb-piece by which said tube may be turned.

5. In an electric switch or cut-out, the combination of a foundation-plate having a depression and an upstanding rim encircling the same, contacts applied to the inner surface of said rim at diametrically opposite 40 points, and a mercury-containing vacuum-tube to electrically connect said contacts swiveled to said plate within said depression.

6. In an electric switch or cut-out, the combination of a foundation-plate, a rim 45 forming a depression at the upper surface of said plate, contacts applied to the inner surface of said rim, and a mercury-containing vacuum-tube swiveled to said plate within said depression and having end-caps to engage said contacts.

In testimony, that I claim the foregoing as my invention, I have signed my name in presence of two subscribing witnesses.

ALFRED A. WOHLAUER.
